DESIGN FOR A TRAY FOR SMOKERS' ARTICLES, DISHES, COASTERS, OR THE LIKE

Henry E. Frederick, Chicago, Ill.

Application June 13, 1940, Serial No. 92,961

Term of patent 3½ years

To all whom it may concern:

Be it known that I, Henry E. Frederick, a citizen of the United States, residing at Chicago, in the county of Cook and State of Illinois, have invented a new, original, and ornamental Design for a Tray for Smokers' Articles, Dishes, Coasters, or the like, of which the following is a specification, reference being had to the accompanying drawing, forming part thereof.

The figure is a perspective view of a tray, for smokers' articles, dishes, coasters, or the like, embodying my new design.

I claim:

The ornamental design for a tray, for smokers' articles, dishes, coasters, or the like, substantially as shown.

HENRY E. FREDERICK.
